SEWING MACHINE FEEDING MECHANISM

Charles W. Dowd, Highland Park, N. J., assignor
to Willcox & Gibbs Sewing Machine Company,
New York, N. Y., a corporation of New York

Application March 25, 1936, Serial No. 70,871

11 Claims. (Cl. 112—214)

This invention relates to sewing machine feeding mechanism and particularly to such a mechanism having a positively driven top feed roller.

The principal object of the invention is to provide means to assist the feed roller in passing over extraordinary thicknesses of work, such as cross seams in very heavy fabrics, which may be passed through the stitch-forming mechanism.

Another object is to actuate said means by movement of the presser-foot and particularly by tilting movement of the foot caused by the passage of the heavy thickness of work under said foot.

The aforesaid and other objects, which will be apparent from the detailed description and drawing, are realized by the present invention, the now preferred embodiment of which is illustrated in the accompanying drawing, wherein—

Figure 1 is a perspective view of a complete machine having the present invention applied thereto;

Figure 2 is a front elevation of a portion of the machine at the free end of the feed-off-the-arm work arm and showing a very heavy thickness of work or cross-seam entering beneath the forward end of the presser-foot and tilting the same upward at said end;

Figure 3 is a similar view with the heavy thickness advanced to about the middle of the foot so that the same is approximately horizontal; and

Figure 4 is a similar view with the heavy thickness still further advanced until it is about to pass from beneath the rear end of the foot.

In the accompanying drawing, the invention is illustrated in conjunction with a feeding mechanism such as set forth in Merritt Patent No. 1,837,468, dated December 22, 1931.

As shown, the machine has a framework comprising two hollow standards 10 and 11 connected by a hollow bridge 12 (corresponding to parts 30, 31 and 32 respectively of said patent). A hollow work-arm extends forward from the upper end of standard 10 in a horizontal part 13 from the outer end of which a part 14 depends vertically. At its upper end the hollow standard 11 curves or bends forward to form the hollow overhanging head portion 15 of the machine frame or casing. The standard 11 and its head portion 15, bridge 12, standard 10, and parts 13, 14 of the work-arm are all preferably integrally formed in one casting. A lower horizontal work-supporting part 16 of the arm extends toward the left and rearward from the lower end of the vertically depending part 14, terminating at its free end (which constitutes the free end of the entire work-arm and

the end off which the work is fed) beneath the overhanging head portion 15 of the machine frame and casing. Part 16 of the work-arm is preferably a trough-like casting and is rigidly but detachably secured to the lower end of part 14. 5 At the free end of said part 16 there is a U-shaped cloth-plate frame 17 properly positioned and removably secured in place. 18 is the throat plate, or cloth plate, which is applied over the frame 17 and properly positioned and secured in place 10 thereon. The cloth plate 18 has needle slots (not shown) and longitudinally extending slots 19 (Fig. 1) to accommodate the rows of teeth on the lower feed dog. 20 is a removable top cover for the part 16 of the work-arm. Other removable 15 caps or covers are also provided to facilitate assembling and access to parts enclosed within the hollow frame-work or casing, the same including a cap 21 at the top of standard 10; an upright cover 22 at the front of the head of the machine; 20 a cover 23 at the left-hand end of the machine. 24 is a folder, shown in dotted outline in Fig. 1, and which may be of any well known suitable construction for interfolding edges of fabric in making felled seams and which is mounted on the 25 work-supporting part 16 of the work-arm. Preferably, for certain classes of work, the folder 24 is movably mounted on the cover plate 20 in the manner set forth in Lewis Patent 1,796,111, dated 30 March 10, 1931.

23 is the needle bar carrying two thread-carrying needles 26, 27, shown in Fig. 2 with their lower ends broken away. Other parts of the stitch-forming mechanism are not shown. 28 is a four-motion feed dog of the lower or bottom feed, having rows of teeth which work upwardly through the slots 19 in the cloth plate 18 in engaging and feeding the work.

30 is the presser-foot bar vertically movable in bearings (not shown) in the head 15 of the machine. 31 is the shank of the presser-foot having a split hub which embraces the lower end of bar 30 and is clamped thereto by tightening screw 32. Shank 31 extends forwardly and downwardly in two spaced fork-like legs 33 and 34, each formed at its lower end to constitute a partly cylindrical cross-head or pivot knob 35, the cylindrical surfaces of both knobs being on a common axis and of the same diameter. Forward of its horizontal pivots or pivotal axis, the presser-foot is solid and 40 includes a normally horizontal portion 36 having therethrough elongated needle openings or slots 37 for the needles 26, 27, respectively, and an upwardly inclined forward end or toe portion 38. Backward from its horizontal pivotal axis, the 45

50

55

presser-foot includes two parallel rearwardly extending side bars 40 and 41, between which the top feed roller is positioned and works, as presently described. The pivot knobs 35, 35 at the lower ends of the legs 33, 34, are engaged in their corresponding pivot sockets in the presser-foot by slight relative sidewise movement. Plate 42 (Fig. 1) at its upper end embraces and is secured by a screw 43 to leg 33 and at its lower end overlies the end of pivot knob 35. There is a similar plate 42, not shown, associated with leg 34, so that the two plates thus prevent disengagement of the pivot knobs from their sockets.

45 is a power-driven intermittently rotated top feed wheel or roller adapted by engagement with the upper surface of the fabric or work to intermittently feed or advance the same the length of one stitch at a time, each feed movement being timed to take place, as usual, while the needle or needles are clear of the work. In the embodiment illustrated herein, the peripheral surface of the feed roller is formed to constitute teeth for gripping the fabric or work to be fed and also to constitute gear teeth through which the roller is rotated by a spiral gear 46 meshing therewith. 47 is a top feed presser-bar of rectangular cross-section having vertical sliding movement, parallel to the presser-foot bar 30, in a suitable slideway in the head 15 of the machine. At its lower end, bar 47 has a right-angle extension branching into two downwardly curved spaced arms 48 between which the roller 45 is journaled on a stud 49. As thus supported the feed-roller 45 is also positioned to engage the top surface of the fabric or work in the space between the side arms 40 and 41 of the presser-foot close to the rear beveled edge of the horizontal solid bottom portion 36 of the presser-foot and thus close to the point where the needles penetrate the work.

The top feed roller 45 is yieldingly pressed downward into gripping engagement with the work by a spring 61 presently described, and may yieldingly move up and down, not only to accommodate itself to variations of thickness of work passing thereunder, but in response to up and down movements of the lower feed dog 28, thereby enabling said roller to continuously maintain its feeding grip upon the work. The roller 45 is power driven and intermittently rotated to feed the work through driving connections from the main shaft (not shown) of the machine, said connections including a vertical rotatable shaft 50, shown in dotted lines in Figs. 3 and 4, extending longitudinally within and movable up and down with the bar 47, and the previously mentioned spiral gear 46 which is secured to the lower end of said shaft.

Means for lifting the top feed roller and presser-foot, both by hand and by foot, and for holding them in elevated position, during introduction of or manipulation of, work and for other purposes, are shown at the left-hand end of Fig. 1. 51 is a short tubular rock-shaft or sleeve rotatable on a stud 52 rigidly projecting from the head 15 of the machine frame or casing. A rock-arm 53, preferably cast integral with the said tubular shaft, extends toward the rear side of the machine where it is engaged by rod 54 depending to a suitable treadle or knee actuated device (not shown), whereby the rod and arm 53 may be pulled downward to the limit of a stop pin 55 against the tension of a coiled spring 56 surrounding the rod and normally tending to hold the arm 53 up to the position in which it is

shown in Fig. 1 in contact with a part which surrounds pivot stud 57. An arm 58, also preferably cast integral with the tubular shaft 51, extends toward the front side of the machine and carries at its outer end a block 59 adapted to engage the underside of a stud 60 projecting from the lower end of the feed roller bar 47. The free end of a flat spring 61 engages and yieldingly presses downward upon said stud 60, said spring at its other end being pivoted on said pivot stud 57 secured to the standard 11 of the machine. An adjusting bolt 63, engaging the top side of the flat spring 61, between its pivot 57 and its engagement with stud 60, serves to increase or decrease the tension of the spring as desired.

As will be readily understood downward pull upon rod 54 by the action of a treadle or knee actuated device (not shown) will lift the top feed roller against the tension of spring 61.

In addition to such means for lifting the top feed roller from a treadle or knee-actuating device, the following means are provided for hand actuation. A bent link 64 pivoted at its lower end to the rock arm 53 by a screw pivot 65 is pivotally connected at its upper end to the outer end of an arm 66 secured to the end of a shaft 67 projecting from and journaled in the wall of the standard 11 of the machine frame, said shaft carrying within said standard means (which need not be herein illustrated or described) which prevent lifting of the presser foot except when the needles are elevated above the cloth plate. 68 is a hand lever fulcrumed to the head of the machine by a screw pivot 69, and carrying a screw stud 70 the shank of which works in a slot in the upper end of a connecting bar 71 which latter at its lower end pivots on the screw pivot 65 beneath the link 64. 72 is a buffer spring secured in a groove along the underside of the hand lever 68 and adapted to contact with a stop stud 73. A spring 74 coiled about the shank of the screw 75 screwed into the connecting bar 71, has one end anchored in an opening in said rod and at its other end bears in a short groove along the upper edge of rock-arm 53. In the normal position of the parts, the pressure of spring 56 on the treadle rod 54 constantly tends to move the parts to their normal position shown in Fig. 1, where the rock-arm 53 contacts with the screw stop 57 and the connecting rod 71 is elevated tilting the hand lever 68 forward with its buffer spring 72 against stop screw 73. In this position of the parts the axis of the pivot screw 70 lies to the left of an imaginary straight line connecting the axes of the pivot screws 65 and 69. To elevate the presser-foot by operation of the hand lever 68 the latter is swung upward causing the pivot screw 70 to act against the lower end of the wall of the slot in connecting bar 71 thereby imparting a longitudinal downward and swinging movement to said rod and moving it and the rock-arm 53, the arm 66 and link 64, to positions in which the end of hand lever 68 contacts a pin 76 projecting from the end wall of the machine head and in which position the axis of the screw 70 will occupy a position slightly to the right of an imaginary straight line connecting the axes of the pivot screws 65 and 69. In this relationship of parts the upward pressure exerted by spring 56 tends to hold the end of lever 68 tightly in engagement with the pin 76 notwithstanding the weaker pressure of the spring 74 tending to swing the upper end of the connecting bar 71 toward the left. The parts 75

are thus temporarily locked in position to hold the feed roller elevated and will so remain until released by a slight forward and downward movement of the hand lever 68 or a slight downward movement of the treadle connections, whereupon the parts will quickly snap back to the position in which they are illustrated in Fig. 1.

The lifting of the feed roller, either by actuation of a treadle or knee device (not shown), or by actuation of the hand lever 68, also lifts the presser foot by means which will now be described. A second arm 77 (similar to arm 58) extends toward the front of the machine from the tubular rock-shaft 51 and carries a block (similar to block 59) which engages under a lug (similar to lug 123 of Fig. 2 of the aforesaid Merritt Patent 1,837,468) or overhanging shoulder on the shank 31 of the presser-foot. Preferably the parts are so positioned or related that the arm 77 begins to lift the presser-foot just after the arm 58 begins to lift the feed roller; but this may be changed as desired.

The construction as hereinbefore set forth in the detailed description is substantially the same as that shown in the aforesaid Merritt patent, except as to certain minor features which will be apparent, and its operation is entirely satisfactory for all ordinary conditions.

But extraordinary conditions, particularly as to thickness of fabric or work passing under the presser-foot, have been encountered in which it has been found desirable to assist the operation of the feed roller by slightly lifting the same in addition to its own capability of elevating itself in passing over humps or extra thicknesses of fabric or work. For example, where a felled cross seam passes through the felling folder 24 (Fig. 1) and under the presser-foot and the fabric is of average thickness, the feed roller will ride up over said cross seam, or elevate itself, without assistance. But if the fabric is very thick, as sometimes occurs, it has been found difficult for the feed roller, by its own action, to ride up over the hump formed by the cross-seam. In other words, under such conditions it is desirable to provide means to assist in lifting or elevating the feed roller over the cross-seam and one embodiment of such means will now be described.

80 is a horizontal arm having an enlarged end 50 grooved transversely to fit about the lower end of the presser-bar 47 for the feed roller, as clearly shown in Fig. 1. A set screw 81, passing through a vertical slot in the enlarged end of arm 80 and into bar 47, rigidly secures the arm 55 to said bar in any desired position of adjustment within the limits of the length of the vertical slot. When the fabric being sewed or operated upon is of average thickness, the arm is secured to the bar 47 with screw 81 passing through the 60 lower end of vertical slot, in which position of the parts the arm does not function or is out of action. But when the thickness of the fabric exceeds the average, or the fabric is very thick, the arm is secured to the bar 47 in a relatively lower position, such as shown in the drawing, so that the arm does function. At its other end or outer end, the arm 80 overlies a shoulder or offset 82 on the shank 31 of the presser-foot.

Figures 2, 3 and 4 show two sections of very 70 heavy or thick fabric being joined by a felled seam, and with a felled cross-seam passing under the presser-foot and feed roller. The fabric is shown in vertical longitudinal section down the middle of the seam, so that there are sixteen thicknesses of fabric at the cross-seam and four

thicknesses at each side thereof. As approximately shown, the side edge of the cross-seam rises almost vertically from the main body of the fabric and presents a hump over which it would be difficult for the feed roller to lift itself, with the result that it would rotate in the corner or space immediately in front of the cross-seam without feeding the work and would thus mar or tear the surface of the fabric at this point. But with the assistance of the lifting 10 means of the present invention, the feed-roller is assisted over such cross-seams and also performs its feeding function at normal feed speed.

In Fig. 2 a cross-seam formed in very heavy fabric is shown as entering beneath the forward 15 upturned end of the presser-foot and has tilted the foot upward at said end with the rear end of the foot resting on the main body of the work. At the same time the upward tilting of the presser-foot has elevated shank 31 and the presser-foot bar 30 until the shoulder 82 on the shank 20 has moved closer to the underside of the arm 80. Further feeding movement of the cross-seam under the presser-foot engages the shoulder 82 with arm 80 and thereby lifts said arm and with 25 it the bar 47 and feed roller 45 until said roller bears upon the top of the cross-seam as shown in Fig. 3. As the feeding of the work and cross-seam continues, the presser-foot tilts downward at its forward end, as shown in Fig. 4, and the 30 reverse of the aforesaid movements begin and continue until the cross-seam passes from beneath the rear end of the presser-foot.

When the fabric is of a thickness which does not require such lifting of the feed roller by the 35 action of the presser-foot, the arm 80 is set on the bar 47 to an inactive position by loosening set-screw 81, sliding the arm 80 upward on bar 47 until the bottom of the slot in the enlarged 40 end of the bar contacts the shank of said screw and the screw then tightened to secure arm 80 to bar 47 in said inactive position.

What is claimed is:

1. A sewing machine including in combination, a work support; a feed member downwardly and 45 yieldingly engaging work on said work support; means for imparting feed movement to said feed member; and means for lifting said feed member in passing over thicknesses in the work such as cross-seams.

2. A sewing machine including in combination, a work support; a rotary feed member downwardly and yieldingly engaging work on said work support; means for imparting feed movement to said feed member; and means for lifting 55 said feed member in passing over thicknesses in the work such as cross-seams.

3. A sewing machine including in combination, a work support; a rotary feed member downwardly and yieldingly engaging work on said 60 work support; means for imparting feed movement to said feed member; an upright bar movable up and down in a portion of the machine above said work support and carrying said feed member; and means for lifting said bar and with 65 it the feed member as the latter passes over thicknesses in the work such as cross-seams.

4. A sewing machine including in combination, a work support; a feed member downwardly and yieldingly engaging work on said work-support; 70 a presser foot downwardly and yieldingly engaging said work on said work-support in advance of its engagement by said feed-roller, said presser-foot being supported to rock or tilt upwardly and downwardly at its forward end; means im- 75

parting feed movement to said feed member; and means actuated by the rocking or tilting of the presser foot to lift the feed member in passing over thicknesses in the work such as cross-seams.

5. A sewing machine including in combination, a work support; a feed member downwardly and yieldingly engaging work on said work support; a presser-foot downwardly and yieldingly engaging said work on said work-support in advance of its engagement by said feed member; driving means imparting feed movement to said feed member; and means actuated by movement of the presser foot in passing over thicknesses in the work such as cross-seams to lift said feed member in passing over said thicknesses.

6. A sewing machine including in combination, a work support; a rotary feed member downwardly and yieldingly engaging work on said work support; a presser-foot downwardly and yieldingly engaging said work on said work-support in advance of its engagement by said feed member; driving means imparting feed movement to said feed member; and means actuated by movement of the presser foot in passing over thicknesses in the work such as cross-seams to lift said feed member in passing over said thicknesses.

7. A sewing machine including in combination, a work arm having a free end off which work is adapted to be fed; stitch-forming mechanism positioned to operate on work advancing along said arm toward the free end thereof; a top feed member engaging work on and feeding the same along said arm toward the free end thereof; driving connections for imparting feed movement to said feed member in a direction to feed the work along said arm toward the free end thereof; and means actuated by thicknesses in the work such as cross-seams to lift the feed member in passing over said thicknesses in the work.

8. A sewing machine including in combination, a work arm having a free end off which work is adapted to be fed; stitch-forming mechanism

positioned to operate on work advancing along said arm toward the free end thereof; a rotary top feed member engaging work on and feeding the same along said arm toward the free end thereof; driving connections for imparting feed movement to said feed member in a direction to feed the work along said arm toward the free end thereof; and means actuated by thicknesses in the work such as cross-seams to lift the feed member in passing over said thicknesses in the work.

9. A sewing machine including in combination, a work arm having a free end off which work is adapted to be fed; stitch-forming mechanism positioned to operate on work advancing along said arm toward the free end thereof; a top feed roller engaging work on and feeding the same along said arm toward the free end thereof; driving connections for imparting feed movement to said feed roller in a direction to feed the work along said arm toward the free end thereof; and means actuated by thicknesses in the work such as cross-seams to lift the feed roller in passing over said thicknesses in the work.

10. A sewing machine including in combination, a work support; a top feed member downwardly engaging and feeding the work along said work support; a bottom feed member upwardly engaging and feeding the work along said work support; means for imparting feed movement to said top and bottom feed members; and means for lifting said top feed member in passing over thicknesses in the work such as cross-seams.

11. A sewing machine including in combination, a work support; a rotary top feed member downwardly engaging and feeding the work along said work support; a bottom feed member upwardly engaging and feeding the work along said work support; means for imparting feed movement to said top and bottom feed members; and means for lifting said top feed member in passing over thicknesses in the work such as cross-seams.

CHARLES W. DOWD.
